CLAIM

The ornamental design for table base, as shown and described.

DESCRIPTION

FIG. 1 is a perspective view of a table base showing my new design;

FIG. 2 is a perspective view thereof in an alternate position for use wherein the front side of FIG. 1 has been rotated to the top;

FIG. 3 is a top plan view thereof;

FIG. 4 is a front elevational view, the rear being a mirror image thereof; and,

FIG. 5 is a right side elevational view, the left side being a mirror image thereof.

The broken line showing of a table top in FIGS. 1, 2, 4 and 5 is for illustrative purposes only.

FIG. 2

FIG. 1

FIG. 3

FIG. 4

FIG. 5
